KNURLING DEVICE

Cernyw F. Jones, Economy, Ind., assignor to
 Perfect Circle Corporation, Hagerstown, Ind.,
 a corporation of Indiana

Application August 24, 1949, Serial No. 112,048

11 Claims. (Cl. 80—5.1)

1

This invention relates generally to a knurling device for knurling the peripheral surface of a cylindrical object and more particularly to a device for knurling predetermined areas on the peripheral surface of a hollow cylindrical article such as a piston for an internal combustion engine.

With continued operation of an internal combustion engine, the pistons and cylinders tend to wear or become distorted with the result that the normal fit of the pistons within the cylinders is lost. This condition is often characterized by "piston slap" and other evidence of excessive looseness. The lack of proper fit between the piston and the cylinder is objectionable since it impairs engine efficiency and has an adverse effect on the economy of operation.

Various means for correcting this condition have been employed, one method involving the expansion of the outer wall or skirt portion of the piston sufficiently to reestablish the normal fit between piston and cylinder. Such expansion may be accomplished, for example, by knurling the outer surface of the piston to form roughened areas on the thrust faces thereof having an interrupted surface comprising projecting portions with intervening depressions. During knurling, the metal is extruded or swaged to a sufficient extent so that the projections formed on the piston surface extend outwardly to the desired increased size whereby the proper fit between the piston and the cylinder is realized.

Although during knurling of a piston the work may be supported or stabilized by hand of the operator, it is generally desirable to provide the knurling device with a suitable work-supporting member or structure which results in more effective stabilization of the piston during knurling and also frees both hands of the operator for manipulation of the knurling mechanism proper. Because the normal contour of a piston is slightly oval or out-of-round, it is necessary that such a work support be designed to permit a limited degree of relative movement between the piston and the work support in order to compensate for the varying piston diameter. In addition, the knurling mechanism preferably comprises an anvil member or other supporting means adapted to engage and support the piston internally while a knurling element engages the exterior of the piston under pressure. However, the interior surface of the skirt portion of a piston is usually quite uneven in the area between the wrist pin bosses because of various protuberances and surface irregularities such as reinforcing ribs,

2

partial machining of the interior surface, and general surface roughness characteristic of cast articles. Thus, the problem is presented of providing a knurling device which will readily accommodate the variations in piston wall thickness while at the same time avoiding any substantial change in knurling pressure against the outer surface of the piston.

Accordingly, one object of my invention is to provide a novel device for knurling the exterior surfaces of pistons which readily accommodates variations in piston wall thickness while maintaining a substantially constant knurling pressure.

Another object of my invention is to provide a novel device for knurling the exterior surfaces of pistons in which a supporting member engages the interior of the piston, a knurling member engages the exterior of the piston, and the spacing between said members is permitted to vary automatically to accommodate protuberances and other irregularities on the interior surface of the piston.

An additional object of the invention is to provide a simple hand-operated device for knurling the exterior surface of a piston in combination with a novel work support adapted to stabilize the piston during knurling while at the same time accommodating slight variations in piston diameter due to the normal out-of-round contour of the piston.

A further object of the invention is to provide a manually operable device for knurling the exterior surface of a piston in combination with novel adjustable stop means for limiting and regulating the extent of the knurled areas on the piston.

A still further object of the invention is to provide a manually operable device for knurling the exterior surfaces of pistons which is simple and rapid in operation and which can be manipulated by an operator with marked convenience and without excessive exertion.

Other objects and advantages of the invention will become apparent from the subsequent detailed description of the invention and the accompanying drawings, in which:

Fig. 1 is a vertical sectional view of a knurling device comprising one specific embodiment of my invention and taken substantially along the line 1—1 of Fig. 4;

Fig. 2 is a top plan view of the device shown in Fig. 1;

Fig. 3 is a vertical sectional view taken along the line 3—3 of Fig. 2;

Fig. 4 is a vertical sectional view taken along the line 4—4 of Fig. 2;

Fig. 5 is a front elevational view of a knurling device comprising a different embodiment of the invention with portions thereof in section;

Fig. 6 is a top plan view of the device shown in Fig. 5;

Fig. 7 is a fragmentary sectional view taken along the line 7—7 of Fig. 5;

Fig. 8 is an end view of the device when viewed from the left in Fig. 5; and

Fig. 9 is an end view of the device when viewed from the right in Fig. 5.

The knurling device comprising the present invention is provided with a pair of cooperating anvil and knurling elements, the anvil element being arranged to support the piston internally while the knurling element bears against the outer surface of the piston. The knurling element may be in the form of a small roller mounted for rotary reciprocating or oscillating movement, the roller being applied to the outer surface of the piston in rolling relation therewith so that the resultant area knurled in one application of the tool comprises a band having a width equal to the width of the roller. Alternatively, the knurling element may also be in the form of a flat bar or elongated member adapted to be reciprocated rectilinearly while in knurling engagement with the exterior of the piston whereby to produce a similar knurled band. In either case the knurling element is usually relatively narrow and traverses the piston circumferentially so that a plurality of such knurled bands are required to cover a desired area longitudinally of the piston. The knurled bands may, of course, be disposed in continuous abutting relation to one another or they may be slightly spaced from each other longitudinally of the piston.

With a piston for an internal combustion engine, it is necessary to knurl only the thrust faces of the piston skirt, i. e., those portions which are subjected to lateral thrust against the cylinder wall due to the position of the connecting rod. Thus, the knurling operation may be restricted to the portions of the piston skirt lying intermediate the wrist-pin holes on opposite sides of the piston. The knurled area preferably starts immediately below the ring grooves at the upper end of the piston and may extend axially or longitudinally for the full length of the piston skirt. If desired, the knurled band at the extreme outer end of the skirt may be spaced differently from the remaining bands in order to position the outermost band as close as possible to the lower edge of the piston.

In addition to effecting expansion of the piston metal by extrusion thereof, in the manner hereinbefore described, whereby to reestablish a proper fit between the piston and the cylinder, the knurled surface obtained by my invention also offers other important advantages. For example, it has been found that better performance is obtained in a reciprocating piston and cylinder, or other like construction, if one of the two surfaces is of an interrupted nature comprising projecting portions with intervening depressions, such as may be provided by knurling. A surface of this character has been found to run cooler than an absolutely smooth surface for pistons as well as other cylindrical objects adapted to reciprocate within a bore. Another advantage inherent in knurling the surfaces of pistons and like articles is found in the improved

wearing qualities of the knurled surface resulting from the hardening effects of cold working the metal. Moreover, the interrupted surface afforded by knurling provides a series of pockets or reservoirs which serve to retain lubricating oil and thereby maintain a continuous supply of lubricant at the surface-contacting areas.

It will be apparent that, in addition to the obvious utility of knurling old or worn pistons in order to expand the same, knurling may also be resorted to in the case of new pistons or original assemblies of pistons within their cylinders in order to attain the other advantages mentioned above. While the knurling device comprising the present invention is designed primarily for knurling pistons, the invention is not limited in this manner but embraces the knurling of the peripheral surfaces of hollow cylindrical articles generally.

The term "knurling" as used throughout the specification and the claims is not limited to the ordinary form of knurling involving grooves arranged in a cross-cross pattern, but rather is used in a broad sense to include any surface formation involving alternate depressed and raised portions regardless of whether one or the other or both of said portions are continuous throughout the area having such formation. Thus, the term includes not only the criss-cross pattern but also a pattern formed by parallel grooves or by isolated indentations resulting in connected raised portions.

As hereinbefore mentioned, an important object of my invention is to provide a knurling device for pistons which is designed to accommodate varying piston wall thicknesses due to internal protuberances or surface irregularities while at the same time avoiding substantial changes in knurling pressure and eliminating the need for manually adjusting or regulating the device during a knurling operation. I accomplish this end broadly by providing a knurling member and a cooperating anvil member pivotally or shiftably mounted for movement toward and away from the knurling member, in combination with a spring means for yieldingly urging the anvil member toward the knurling member. The yieldable urging of the one member toward the other permits a variation in spacing between the members upon contact of the anvil member with protuberances on the interior surface of the piston skirt while the knurling member bears with substantially constant pressure against the exterior surface of the skirt.

55 Form shown in Figs. 1—4

Referring now to Figs. 1 to 4 of the drawings, which show by way of illustration one specific embodiment of my invention, the device comprises a generally rectangular body member or base 10 having depending end walls 11 and front and rear walls 12 and 13, respectively, for supporting the device on a work bench or other horizontal work surface. At one end of the base 10 is a raised bed 14 comprising a machined work-supporting surface which extends transversely of the device. A pair of stabilizing wings 15 of semi-rigid or resilient construction are slidably mounted on the bed 14 by means of a pair of upright studs 16 which extend through the base portions of the wings 15. Retaining nuts, indicated at 17 (Fig. 1) are attached to the lower ends of the studs 16 and are slidably retained in an elongated T-shaped slot 18 in the bed 14. The studs 16 are threaded at their upper ends into a pair of

clamping nuts 19 for adjustably clamping the wings 15 in desired spaced relation on the bed 14.

As shown in broken lines in Figs. 1, 3 and 4, a piston 20 may be disposed above the bed 14 and may be stabilized against twisting movement during knurling by engagement of the wings 15 at opposite sides of the piston. Thus, by adjustment of the studs 16 and the nuts 19, the wings 15 may be positioned at any desired spacing dependent upon the diameter of the piston to be knurled, the wings 15 exerting sufficient resilient pressure to stabilize the piston 20 longitudinally but still permitting rotation of the piston on its axis during the knurling operation and accommodating the normal out-of-round piston contour, as hereinafter described in detail.

In this embodiment of the invention an elongated bar-type knurling element is utilized. To this end, an elongated groove 21 is provided adjacent the inner edge of the bed 14 and parallel to the T-shaped slot 18. Slidably disposed within the groove 21 is an elongated knurl carrier or slide 22 having a rack or gear teeth 23 (Fig. 3) at its bottom side. The elongated bar-type or flat knurling element, indicated at 24, is detachably secured in the knurl carrier 22 by means of a pair of set screws 25 having pointed inner ends which are received within offset notches or cavities 26 in the ends of the knurling element 24 whereby the knurl 24 is held tightly against the slide 22 with the upper or work face of the knurled projecting slightly above the surface of the bed 14 (Figs. 1 and 3). It will be understood that the work face of the knurling element 24 is formed with a roughened knurling surface, of the character hereinbefore described, for contacting and knurling the outer periphery of the piston 20.

For driving the knurl 24, an elongated drive shaft 27 is journaled at one end in a bore 28 (Fig. 1) provided in the base 10 and extends at its opposite end through an end wall 11 and is journaled therein, as at 29. A set screw 30 is provided for engaging a groove in the shaft 27 to prevent endwise movement thereof. A pinion 31 is formed at the inner end of the shaft 27 and meshes with the rack 23. A hand crank 32 extends through the outer end of the shaft 27 for manually driving the knurl 24 and is secured in adjusted position by means of a set screw 33. Upon rotation of the hand crank 32 in alternate directions, reciprocating sliding movement in a rectilinear path is imparted to the knurling element 24 whereby to produce a knurled band on the outer periphery of the piston 20.

For controlling and limiting the length of the knurl tracks on the piston 20, a pair of stops are provided for limiting the rectilinear movement of the knurling element 24. To this end, a pair of supports 34 (Fig. 3) are secured to the front and rear walls 12 and 13 by means of a plurality of screws 36, and a pair of elongated screws or adjustable stop members 37 are threaded through the upper portions of the supports 34 and project into the opposite ends of the groove 21. Each of the stop screws 37 is provided with a locking nut 38 for fixing the adjusted position of the stop members, the opposite ends of the knurl carrier 22 being adapted to engage or abut the inner ends of the screws 37 whereby to limit the extent of reciprocating sliding movement of the knurl carrier 22 and the knurling element 24.

To provide an anvil support, a bell crank, indicated generally at 39 (Fig. 4), having a generally horizontal short arm 41 and a depending

long arm 42, is pivotally supported on the base 10 by means of a fulcrum pin or pivot shaft 43 journaled between a pair of upright lugs or ears 44 extending upwardly from the base 10. An elongated anvil-supporting arm 46 is rigidly attached, as by a pair of screws 47, to the end of the short arm 41 of the bell crank 39 and extends parallel to the drive shaft 27 toward the open end of the piston 20. The outermost end of the arm 46 is provided with a pair of spaced projections between which is mounted for free rolling movement an anvil member in the form of a hard smooth-surfaced roller 48 having approximately the same width as the knurling element 24. The anvil roller 48 is carried on a pin 49 and is positioned in radial alignment with respect to the knurling element 24 for engaging the inner periphery of the piston 20 as the knurling element traverses the outer surface of the piston.

The long arm 42 of the bell crank 39 extends downwardly through a slot or opening 51 in the base 10 and is bifurcated at its lower end, as at 52 (Fig. 4), a swivel in the form of a pin or shaft 53 being journaled through the bifurcated portions thereof. An elongated spring-loading device, indicated generally at 54, extends horizontally between the walls 12 and 13 of the base 10 and coacts with the bell crank 39 for applying adjustable yielding pressure against the leg 42 whereby the anvil roller 48 is normally urged toward the knurling element 24. The spring-loading device 54 comprises an elongated screw 55 having terminally threaded portions and extending longitudinally through a transverse aperture 56 in the shaft 53 between the bifurcated end portions 52 of the leg 42 and projecting through an opening 57 in the rear wall 13. The forward end of the screw 55 extends through an enlarged concentric bore 58 in the front wall 12 of the base 10. The screw 55 is also threaded through a swivel in the form of a pin or shaft 61 rotatably supported at one end in a boss 59 formed on the inner face of the front wall 12 and at its other end in the adjacent end wall 11. Encircling the screw 55 is a helical spring 62 adapted to apply yielding pressure against the shaft 53 through a thrust collar 63. A spring load adjusting nut 64 is threaded at the rear end of the screw 55 and bears against the opposite end of the spring 62 through a similar thrust collar 66. Another thrust collar, comprising a loosely mounted thrust washer 67 and a thrust washer 68 rigidly secured to the screw 55, is disposed on the opposite side of the shaft 53 for engaging the latter and urging the anvil roller 48 to released position, as hereinafter described in detail. A handle 69 is attached to the forward end of the screw 55 for rotating the same.

By adjusting the nut 64, the tension of the spring 62 can be regulated to control the spring pressure exerted on the leg 42 of the bell crank 39 and thereby regulating the knurling pressure, i. e. the pressure under which the skirt portion of the piston 20 is pressed against the knurling element 24 by means of the internal anvil roller 48. A jam or lock nut 70 is carried on the screw 55 beyond the adjusting nut 64 for locking the latter in place after the spring tension has been adjusted to any desired extent.

The operation of the spring loading device 54 is as follows: In the position shown in Fig. 4, the screw 55 has been moved forwardly by its threaded connection with the shaft 61 so that a slight clearance, indicated at 71, is established

between the thrust washer 67 and the shaft 53. Thus, the full pressure of the spring 62 is brought to bear on the shaft 53 thereby urging the bell crank 39 in a clockwise direction, as viewed in Fig. 4, and causing the anvil roller 48 to be pressed toward the knurling element 24 with the skirt portion of the piston 20 being clamped therebetween. As described above, the knurling pressure may be controlled by adjusting the nut 64 to regulate the tension of the spring 62.

By means of the handle 69, the screw 55 may be screwed inwardly of the device at its threaded connection with the shaft 61 until the thrust washer 67 abuts the shaft 53 thereby rendering the spring load ineffective as the clearance 71 is taken up. At this point, continued inward movement of the screw 55 causes the leg 42 to be rocked rearwardly of the device and the anvil roller 48 to be moved away from the interior surface of the piston 20 to released position as the bell crank 39 rotates in a counterclockwise direction about the fulcrum pin 43, as viewed in Fig. 4. With the roller 48 and the knurling element 24 in spaced relation, the skirt of the piston 20 may be withdrawn or inserted to the desired extent. As the leg 42 swings rearwardly of the device in an arcuate path during movement of the anvil roller 48 to released position, the rear end of the screw 55 swings slightly in a downward direction, as viewed in Fig. 4. To accommodate this pivotal movement of the screw 55, the swivel shafts 61 and 53 rotate freely in their respective supporting structures, the bifurcated end 52 of the leg 42 and the enlarged bore 58 in the front wall 12 providing sufficient clearance to permit the screw 55 to assume the necessary angular position.

During the inward movement of the screw 55, the tension setting of the spring 62 is not materially disturbed since the spring tension is determined by the relative position of the adjusting nut 64 on the screw 55. Inward movement of the screw 55 from the position shown in Fig. 4 until the clearance 71 is taken up will result in a very slight decrease in the spring tension setting equivalent to the extent of the clearance 71, but this change is of no practical consequence. Thus, it will be seen that the anvil roller 48 can be backed away from the skirt portion of the piston 20 without unloading the spring 62 or otherwise changing the spring tension setting.

To return the device to knurling position, the handle 69 is operated in reverse fashion whereby the screw 55 is moved forwardly of the device through the shaft 61 and the tension of the spring 62 acting on the shaft 53 pivots the bell crank 39 to swing the anvil roller 48 into contact with the inner surface of the piston 20 with sufficient pressure to sink the ridges on the knurling element 24 into the outer surface of the piston skirt. Further movement of the bell crank 39 and its leg 42 is prevented, and forward movement of the screw 55 is continued until the slight clearance 71 is reestablished between the shaft 53 and the thrust washer 67. Thus, the spring 62 is returned substantially to its original tension and the full spring load is again imposed on the shaft 53. Once the clearance 71 is obtained, further operation of the handle 69 is unnecessary since the establishment of the slightest clearance at this point permits the full spring tension, as determined by the setting of the nut 64, to be applied against the shaft 53.

In knurling a piston with the device shown in Figs. 1 to 4, the piston 20 is first positioned on

the bed 14 with the skirt portion thereof extending between the anvil roller 48 and the knurling element 24 to the desired extent while the anvil supporting arm 46 is in released position. The stabilizing wings 15 are then slid into contact with the exterior of the piston and are secured in position by means of the studs 16 and the clamping nuts 19. Upon adjustment of the nut 64 to obtain the desired tension in the spring 62 and upon backing off of the screw 55 by means of the handle 69 to return the arm 46 to operating position, the desired knurling operation may then be carried out by adjusting the stop screws 37 to obtain a knurl track of desired length and then rotating the hand crank 32 in alternate directions to effect reciprocating rectilinear movement of the knurl carrier 22 and the knurling element 24.

Rotation of the hand crank 32 results in relative movement between the knurling element 24 and the piston 20 circumferentially of the latter and, because the skirt portion of the piston 20 is clamped between the anvil roller 48 and the knurling element 24, reciprocating sliding movement of the knurling element 24 also causes simultaneous rotation of the piston 20 on its axis whereby to form an arcuate knurled band on the outer periphery of the skirt, as hereinbefore mentioned.

During knurling, the piston 20 is held squarely against the face of the knurling element 24 by means of the clamping action of the anvil roller 48 forcing the piston skirt against the knurl. The semi-rigid stabilizing wings 15, which are clamped in position on the bed 14 by means of the studs 16 and the nuts 19, engage the sides of the piston 20 to stabilize the piston against twisting movement in a horizontal plane. The stabilizing wings 15, while adapted to resist any tendency toward twisting movement of the piston, are also sufficiently flexible or resilient to accommodate slight variations in the effective diameter of the piston 20 as a result of its normal out-of-round contour. In other words, as the piston 20 rotates on its axis while firmly clamped between the anvil roller 48 and the knurling element 24, the stabilizing wings 15 will flex inwardly and outwardly to a slight extent as they ride on the periphery of the piston whereby to accommodate variations in piston diameter while at the same time effectively stabilizing the piston against twisting movement longitudinally thereof.

During the course of a knurling operation, if the anvil roller 48 encounters internal protuberances or other surface irregularities on the interior of the piston skirt, it will be seen that yielding application of the anvil roller 48, by the spring loading device 54, against the inner surface of the piston skirt permits the roller 48 to be forced away from the protuberance, the bell crank 39 rocking in a counterclockwise direction about the fulcrum pin 43, as viewed in Fig. 4, and the vertical leg 42 being forced rearwardly of the device against the action of the spring 62. The slight compression of the spring 62 resulting from such rocking movement will have no significant effect on the pressure with which the skirt portion of the piston 20 is clamped between the anvil roller 48 and the knurling element 24. Thus, my device provides for substantially constant knurling pressure, as predetermined by the setting of the adjusting nut 64 and the lock nut 70, even when the spacing between the roller 48 and the knurl 24 varies as the roller passes over surface irregularities on the interior of the piston skirt.

Form shown in Figs. 5 to 9

This embodiment of my invention is similar in principle to the form described above and differs primarily in that the knurling element is in the form of a roller having geared operating connections with a hand lever. In addition, the anvil supporting arm is pivotally mounted directly on the base structure, thereby eliminating the bell crank arrangement shown in Figs. 1 to 4, and also a modified form of the spring loading device is utilized.

In this form of the invention an elongated body member or base structure 81 is provided with a narrow upright work support 82 at one end thereof. An elongated bar 83 extends transversely through the work support 82 and is secured in position therein by means of a set screw 84 (Fig. 6). Slidably mounted at opposite ends of the bar 83 are a pair of socket members 86 each carrying an upright semi-rigid stabilizing wing 87 which is adapted to engage the outer periphery of a piston, as indicated by broken lines at 90, the piston being supported on the work support 82. The socket members 86 are slideable along the bar 83 to accommodate pistons of varying diameter and are secured in desired spaced relation on the bar 83 by means of a pair of clamping screws 89 extending through the sockets 86 into engagement with a pair of coacting flattened portions 91 at opposite ends of the bar 83.

A knurling roller 92, which projects upwardly slightly above the upper surface of the work support 82 (Fig. 5), is secured by a screw 93 to one end of a short shaft 94 which is journaled in a bearing block 95 extending upwardly from the base 81 and rigidly secured thereto, as by a pair of screws (Fig. 6). Gear teeth, indicated at 97 and comprising a pinion, are provided on the shaft 94 adjacent the knurling roller 92, and the opposite end of the shaft 94 is formed with an annular flange 98 adapted to engage the side face of the bearing block 95 for retaining the shaft 94 against endwise movement. A gear sector 99 in meshed engagement with the gear teeth 97 is mounted on the end of a shaft 101 which is also journaled in the bearing block 95 at the lower portion thereof below the shaft 94. The shaft 101 is keyed to one end of an elongated drive shaft 102 journaled at its opposite end (Fig. 5) in the base 81 and extending beyond the base 81, as seen on the right side in Fig. 5. The outermost end of the shaft 102 is provided with a hand lever 103 secured thereto by a set screw 104 for effecting rotary oscillating movement of the knurling roller 92. As hereinafter described in detail, a pair of adjustable stop members 106 are slidably mounted in a T-shaped slot 107 in the end wall of the base 81 adjacent the hand lever 103 for limiting the extent of oscillating or back and forth movement of the latter whereby to regulate the length of the knurl track on the piston 88.

To provide an anvil support, a block 108 is pivotally mounted at one end thereof on a shaft or pin 109 journaled on the base 81 between a pair of upright ears or lugs 110. Secured to the block 108 by means of a pair of screws 111 and extending longitudinally therefrom is an elongated anvil-supporting arm 112 carrying an anvil roller 113 at its opposite end in radial alignment above the knurling roller 92, the roller 113 having substantially the same width and diameter as the roller 92. A spring loading device, indi-

cated generally at 114, coacts with a portion of the base structure 81 and the block 108 for yieldingly urging the anvil arm 112 and the anvil roller 113 toward the knurling roller 92.

The spring loading device 114 comprises an elongated screw 116 having terminally threaded portions and extending downwardly through an enlarged bore 117 (Fig. 5) in the block 108. The lower end of the screw 116 is received within a similar enlarged bore 118 formed in the base structure 81 and is threaded through a swivel in the form of a pin or shaft 119 journaled in the base structure 81 and extending transversely of the bore 118. A helical spring 121 encircles the screw 116 and bears at one end against the outer face of a cup-like bridge member or thrust member 122 which seats on the upper side of the block 108 and the arm 112. The spring 121 is retained at its other end by a tension adjusting nut 123 and a thrust collar 124 comprising a plurality of thrust washers. A lock nut or jam nut 126 is also provided adjacent the nut 123 for locking the latter in place in order to maintain any desired tension setting of the spring 121. A thrust collar 127 is rigidly mounted on the screw 116 and is received within the member 122, the diameter of the thrust collar 127 being less than the internal diameter of the member 122. A handle 128 is provided at the outer end of the screw 116 for effecting rotation of the latter.

As viewed in Fig. 5, the screw 116 is screwed downwardly through its threaded connection with the swivel 119 a sufficient amount so that a slight clearance, indicated at 129, exists between the thrust collar 127 and the under side of the thrust member 122. In this position the full load of the spring 121 is imposed on the arm 112 thereby yieldingly urging the anvil roller 113 toward the knurling roller 92, the piston 88 having its skirt portion clamped between the rollers 113 and 92.

To release the knurling pressure, the screw 116 is screwed outwardly by means of the handle 128. As the clearance 129 is taken up, the thrust collar 127 engages the member 122, and upon continued outward movement of the screw 116, the member 122 is lifted upwardly from the block 108 and the arm 112. During backing-off of the screw 116, a helical spring 131 disposed in a cavity 132 in the body structure 81 and bearing against the bottom face of the block 108 causes the latter to pivot upwardly about the fulcrum pin 109 thereby swinging the arm 112 upwardly and disengaging the anvil roller 113 from the interior surface of the piston 88. As the arm 112 is thus moved to released position, the screw 116 pivots slightly to the right, as viewed in Fig. 5, as the swivel 119 rotates to accommodate the angular upwardly pivoted position of the arm 112. The enlarged bore 117 in the block 108 and the bore 118 in the base structure 81 are of sufficient size to provide the necessary clearance required to accommodate the pivotal movement of the screw 116.

As in the device 54 of Figs. 1 to 4, it will be seen that the spring load of the device 114 can thus be released from the arm 112 without changing the setting of the tension adjusting means and without otherwise materially altering the spring pressure.

To return the spring loading device 114 to knurling position, the screw 116 is screwed downwardly thereby forcing the arm 112 downwardly against the pressure of the spring 131, and when the anvil roller 113 contacts the interior of the skirt portion of the piston 88 the screw 116 is

screwed inwardly a slight distance farther until the clearance 129 is reestablished and the full spring load is thereby brought to bear on the arm 112 whereby to sink the ridges of the knurling roller 92 into the metal of the piston skirt.

During use of the knurling device, the piston 88 rests on the work support 82 while the skirt portion of the piston is inserted between the rollers 113 and 92 to the desired extent with the anvil supporting arm 112 in released position. When the spring loading device 114 is manipulated to return the arm 112 and roller 113 to knurling position under a predetermined spring pressure as regulated by the adjusting nut 123, the knurling roller 92 is then rotated by oscillating movement of the hand lever 103 back and forth between the stop members 106. As in the previously described embodiment of my invention, the piston is stabilized during knurling by the clamping action of the rollers 113 and 92 and also by the resilient pressure of the stabilizing wings 87 which resist any tendency toward twisting of the piston during knurling while at the same time flexing inwardly and outwardly to accommodate slight variations in the diameter of the piston 88 as the latter rotates on its axis. As the anvil roller 113 encounters protruding conformations on the inner surface of the piston skirt, the roller 113 is forced away from the roller 92 without substantially changing the knurling pressure.

An important advantage of this embodiment of my invention is in the speed and ease of manipulation of the manual means for driving the knurling roller. In general, the stroke on the hand lever 103 may conveniently be less than 90° for piston diameters up to 5½ or 6 inches and, as a result, the knurling mechanism may be manipulated quite rapidly and with minimum fatigue and marked convenience to the operator. In addition, the location of the knurling roller 92 and the general construction of the device in the knurling area are such that ample illumination and space are provided for micrometer measurements and the like.

Another important advantage of the present form of the invention resides in the arrangement of the stop means for regulating the length of the hand lever stroke and thereby the extent of the knurl track on the piston. The knurl tracks on the piston may be conveniently centered by marking a line or other indicia on the inner end of the piston skirt 90° from one of the wrist pin holes and then lining this mark up with a groove, such as shown at 133 in Fig. 7, provided at the top of the knurl shaft 94. By thus aligning the knurling area of the piston with the knurl shaft, the hand lever 103 will then be centrally located with respect to a series of graduations 134 (Fig. 9) which are provided on the end face of the base structure 81 for each of the slideable stop members 106. By this arrangement the stop members 106 may then be accurately positioned by means of the graduations 134 to permit knurling of the piston to a predetermined distance on either side of the previously inscribed center line. If desired, a chart or table can be readily prepared which will indicate the number of graduations 134 to be employed in positioning each of the stop members 106 for any desired length of knurl track.

Although the invention has been described in detail with reference to certain preferred structural embodiments, it will be understood that various modifications and equivalent structures may be resorted to without departing from the

scope of the invention as defined in the appended claims.

I claim:

1. A device for knurling the thrust faces of the skirt portion of a piston, comprising a base, a movable knurl-carrying member mounted on said base, a knurling element carried by said knurl-carrying member and adapted to engage the exterior surface of the piston skirt, a manually operable driving means having driving engagement with said knurl-carrying member for actuating the latter whereby to operate the knurling element, said driving means including a manually operable member, a pair of abutments adjustably mounted on said base on opposite sides of one of said members in the path of movement thereof to limit the movement of the knurling element thereby to limit the length of the knurled band formed on the piston skirt, an anvil element mounted on said base in shiftable relation to said knurling element and adapted to engage the interior of the piston skirt, and means yieldingly urging said anvil element toward said knurling element.
2. A device for knurling the thrust faces of the skirt portion of a piston, comprising a base having a slideway therein, a knurl-carrying member slidably disposed in said slideway for reciprocating movement therein, a knurling element mounted on said knurl-carrying member and adapted to engage the exterior surface of the piston skirt, manual means for effecting reciprocating sliding movement of said knurl-carrying member within said slideway, an anvil member mounted on said base in shiftable relation to said knurling element and adapted to engage the interior surface of the piston skirt, and means for yieldingly urging said anvil member toward said knurling element.
3. A device for knurling the thrust faces of the skirt portion of a piston, comprising a base having a slideway therein, a knurl-carrying member slidably disposed in said slideway for reciprocating movement therein and having gear teeth thereon, a knurling element mounted on said knurl-carrying member and adapted to engage the exterior surface of the piston skirt, a drive shaft having a pinion mounted thereon in operative engagement with said gear teeth, manual means for rotating said drive shaft in alternate directions whereby to effect reciprocating sliding movement of said knurl-carrying member and said knurling element, an anvil member mounted on said base in shiftable relation to said knurling element and adapted to engage the interior surface of the piston skirt, and means for yieldingly urging said anvil member toward said knurling element.
4. A device for knurling the thrust faces of the skirt portion of a piston, comprising a work support for holding a piston during knurling and for stabilizing the piston during rotation thereof on its axis, and knurling mechanism comprising a manually operable knurling element adapted to engage the exterior surface of the piston skirt and an anvil member adapted to engage the interior surface of the piston skirt, said anvil member being shiftable mounted relative to said knurling element and being provided with means for yieldingly urging the same toward said knurling element, said work support comprising a pair of slidably mounted semi-rigid wings adapted to engage the exterior of the piston at opposite sides thereof whereby to retain the piston against longitudinal twisting movement during knurling,

said wings being sufficiently flexible to accommodate slight variations in diameter of the piston as the latter rotates on its axis between said wings and while the skirt portion thereof is clamped between said knurling element and said anvil member.

5. A device for knurling the thrust faces of the skirt portion of a piston, comprising a base, reciprocable knurling means movably mounted on said base and adapted to engage the exterior surface of the piston skirt, manually operable driving means for effecting reciprocation of said knurling means, an anvil member mounted on said base in shiftable relation to said knurling means and adapted to engage the interior surface of the piston skirt, pressure applying mechanism for yieldingly urging said anvil member toward said knurling means, and adjustable stop members engageable by one of said means for limiting the extent of reciprocating movement of said knurling means whereby to regulate the length of the knurl track on the piston skirt.

6. A device for knurling the thrust faces of the skirt portion of a piston, comprising a base, knurling means mounted for reciprocating sliding movement in a rectilinear path on said base and including a flat bar-type knurling element adapted to engage the exterior surface of the piston skirt, manually operable driving means having a driving connection with said knurling means for effecting said reciprocating sliding movement of said knurling means, an anvil member mounted on said base in shiftable relation to said knurling means and adapted to engage the interior surface of the piston skirt, means for yieldingly urging said anvil member toward said knurling means, and adjustable stop means coacting with opposite ends of said knurling means for regulating the extent of said reciprocating sliding movement.

7. A device for knurling the thrust faces of the skirt portion of a piston, comprising a generally horizontal base, a knurling member mounted on said base and adapted to engage the exterior surface of the piston skirt, manual means for driving said knurling member, a bell crank pivotally mounted on said base and comprising a generally horizontal leg disposed above said base and a depending leg extending below said base, an elongated anvil-supporting arm secured to the horizontal leg of said bell crank and carrying an anvil member adapted to engage the interior surface of the piston skirt in substantial alignment with the knurling member, and a releasable spring loading mechanism extending generally horizontally through said base and coacting with the lower end of the depending leg of said bell crank for yieldingly urging said anvil member toward said knurling member under predetermined substantially constant pressure.

8. The device of claim 1 further characterized in that said knurl-carrying member comprises a knurl shaft journaled on said base, that said knurling element is in the form of a roller mount-

ed on said knurl shaft, and that said manually operable driving means has a geared connection with said knurl shaft for effecting rotary oscillating movement of said knurling roller.

5. The device of claim 1 further characterized in that said knurl-carrying member comprises a knurl shaft journaled on said base, that said knurling element is in the form of a roller mounted on said knurl shaft, that said knurl shaft is provided with gear teeth, and that said manually operable driving means comprises a drive shaft journaled in said base and having a gear sector mounted thereon in operative engagement with said gear teeth on said knurl shaft, and a hand lever secured to said drive shaft for effecting rotary oscillating movement of said knurling roller.

10. The device of claim 1 further characterized in that said knurl-carrying member comprises a knurl shaft journaled on said base, that said knurling element is in the form of a roller, that said manually operable driving means includes a hand lever for effecting rotary oscillating movement of said roller, and that said pair of abutments coact with said hand lever for limiting the extent of said rotary oscillating movement.

15. The device of claim 1 further characterized in that said anvil element is carried by an elongated anvil-supporting arm pivotally mounted on said base with said anvil element in substantial alignment with said knurling element, that said means yieldably urging said anvil element toward said knurling element comprises a releasable spring loading mechanism coacting between said base and said anvil-supporting arm for yieldingly urging said anvil element toward said knurling element under a predetermined substantially constant pressure, that spring means 20 is provided for urging said anvil-supporting arm away from said knurling element when said spring loading mechanism is in released position, and that said mechanism comprises an elongated member extending into said base, an adjustable helical spring encircling said elongated member, and a thrust member loosely carried on said elongated member for transmitting the pressure of said helical spring to said anvil-supporting arm.
